PORTABLE TRAFFIC WARNING SIGNAL

Clyde E. Beimfohr, Mascoutah, Ill., Wayne M. Beimfohr, Overland, Mo., and Albert F. Beimfohr, Mascoutah, Ill., assignors to Triple B Manufacturing Co., Inc., Mascoutah, Ill., a corporation of Illinois

Application April 8, 1957, Serial No. 45,643

Term of patent 14 years

(Cl. D72—1)

FIG. 1.

FIG. 2.

FIG. 3.

FIG. 4.

FIG. 5.

Fig. 1 is a front elevation of a portable traffic warning signal embodying our new design;

Fig. 2 is a top plan view of Fig. 1;

Fig. 3 is a rear elevation of Fig. 1;

Fig. 4 is a right side elevation of Fig. 1; and,

Fig. 5 is a left side elevation of Fig. 1.

The broken line portions on the drawing are for illustrative purposes only.

We claim:

The ornamental design for a portable traffic warning signal, substantially as shown and described.
